UNITED STATES PATENT OFFICE

ALEXANDER JAMESON, OF INDIANAPOLIS, INDIANA.

CONTROLLER FOR MUSICAL INSTRUMENTS.

1,179,187.

Specification of Letters Patent. Patented Apr. 11, 1916.

Application filed December 16, 1912. Serial No. 736,939.

To all whom it may concern:

Be it known that I, ALEXANDER JAMESON, a citizen of the United States, residing at Indianapolis, in the county of Marion and State of Indiana, have invented a new and useful Controller for Musical Instruments, of which the following is a specification.

The object of my invention is to produce mechanism by means of which the operation 10 of a mechanical musical instrument may be controlled as to all of its operations by one hand of an operator who may, if desired, be at a point distant from the instrument so that the operator may, while facing an 15 audience in order to perform as a singer, also control the operation of the mechanical musical instrument and cause it to thereby produce an accompaniment to his other performance.

20 The accompanying drawings illustrate my invention as applied to a player piano.

Figure 1 is a front elevation largely dia- 25 grammatic, illustrating the general arrangement of the various portions of my device; Fig. 2 a detail, about full size, of my im- 30 proved hand piece, one of the mating por- tions of the main body having been removed; Fig. 3 a perspective view of a desirable means for operating one of the throttle valves; Fig. 4 a detail of a convenient form of 35 relief valve; Fig. 5 a sectional view, somewhat larger than full size, of the pneumatic shown in Fig. 3; Fig. 6 a section of a pair of mating plates by means of which con- 40 nection may be conveniently made between my improved hand piece and the various elements of my invention which are to be mounted most conveniently within the cas- 45 ing of the musical instrument; Fig. 7 a plan 50 of one of the plates shown in Fig. 6; Fig. 8 a fragmentary detail of the means for automatically compensating for variations in vacuum in the main chamber; and Fig. 9 a view similar to Fig. 1 but showing my 55 improvements so embodied that the finger operated controlling members are set in the key-board of the piano; Fig. 10 a front ele- 60 vation of a modified tempo controller, and Fig. 11 a diagram of the string-striking 65 mechanism.

While no attempt has been made to show the various parts to any particular scale it will be noted that in Fig. 1 the various tubes and other portions which are shown in full

lines as part of my invention are relatively 55 largely exaggerated in size while Figs. 2, 3 and 4 are practically full size.

In Fig. 1 of the drawings, I have indicated most of the piano and the usual automatic player mechanism in dotted lines in 60 order to avoid confusion.

In the drawings 10 indicates the usual 65 vacuum chamber of a player piano connected by pipes 11 and 12 with the wind trunks 13 and 14 respectively, said wind trunks leading to the bass and treble ends respectively of any desirable form of pneumatic action 15 by means of which the string-striking mechanism of the piano may be manipulated. Manipulation of the 70 various elements of the pneumatic action 15 is controlled by a music sheet 16 carried over the usual tracker board 17 by means of a pneumatic sheet-motor 18 which is connected by a trunk 19 with the chamber 10. The 75 piano may be provided with a soft pedal rail 21 actuated through a link 22 by a power pneumatic 23 connected in the usual manner by pipe 24 with chamber 10. This pneumatic 23 may be of any common form 80 provided with a controlling pneumatic, said controlling pneumatic having a tube 25 leading into it by means of which the action of the power pneumatic 23 may be controlled in the usual manner by opening and closing 85 communication between the atmosphere and the interior of pipe 25.

Similarly the piano will be provided with a sustaining rail 27 by the manipulation of 90 which the dampers of the string-striking mechanism may be held away from the strings in the usual way and this rail is manipulated through a link 28 by means of a power pneumatic 29 of ordinary form connecting pipe 31 with chamber 10 and 95 controlled in its action through the medium of a pipe 32. The apparatus thus far described does not differ from apparatus now commonly known and in the market.

The fundamental element of my improve- 100 ment is the finger-controlled mechanism, preferably embodied in a hand piece, illus- trated in Fig. 2, which may be grasped in one hand of the operator and its various elements or members controlled by com- paratively small movements of the fingers and thumb of the holding hand. This hand piece comprises a main body 41 which may

be conveniently made in mating halves so as to form a hollow body of convenient size and shape to be readily grasped in the hand in such manner that the ends of the fingers 5 and thumb may be free for convenient movements. In the present drawings, this hand piece is shown as provided with four pockets 42, 43, 44, and 45, in which are mounted hollow rubber balls or bodies 42', 10 43', 44', and 45', respectively. Leading from the balls 42', 43', 44', and 45' are tubes 46, 47, 48, and 49, respectively, which are brought together and, in association with other similar tubes to which reference will 15 be made, are united into a flexible cable 51, one end of which is secured to the lower end of the hand piece 41. The cable 51 may be of any desired length and at its opposite end the several tubes, which go to make up this 20 cable, are conveniently connected to individual nipples 52 carried by a plate 53 which may be removably clamped upon a similar plate 54 mounted within the casing of the piano, said plate being provided with nipples 55 corresponding with the nipples 52 and having tubes 61, 62, 63, 64, 65, 66, 67, 25 and 68 leading therefrom to various points within the piano casing. Also mounted within the main body 41 are distendable and 30 collapsible pneumatics 71, 72, 73, and 74 which may conveniently be of the form shown in Fig. 5, or some other form. Leading from the pneumatics 71, 72, 73, and 74 are pipes 75, 76, 77, and 78 respectively and 35 which also form part of cable 51 and leading to plate 53 the several tubes or pipes forming cable 51 are connected to the nipples of plate 53 in such manner that tube 46 connects with tube 68, tube 47 with tube 62, 40 tube 48 connects with tube 61, tube 49 connects with tube 67, tubes 75 and 76 connect with tubes 66 and 65 respectively, and tube 77 and 78 connect with tubes 64 and 63 respectively. The pneumatics 71 and 72 are 45 connected to be operated simultaneously in opposite directions by means of an arm 81 carried by a plunger 82 reciprocably mounted within hand piece 41 and normally urged outwardly from the hand piece by a spring 83. Similarly the pneumatics 73 and 74 are 50 connected for simultaneous opposite manipulation by an arm 84 also carried by the plunger 82, the said plunger having a thumb piece 85 at its outer end by means of which 55 it may be readily moved inwardly by the thumb of the operator grasping the hand piece 41. Located in the wind trunk 19, which leads from the motor 18 to chamber 10, is a throttle valve 86 provided with an 60 operating arm 87 which is connected to a rod 88 the ends of which are carried by the movable members of a pair of pneumatics 91 and 92 which are connected to pipes 66 and 65 respectively, the arrangement being 65 such that, when the valve 86 is wide open,

one of the pneumatics will be expanded and the other pneumatic will be collapsed.

Arranged beneath the tracker board 17 are two pneumatics 93 and 94 the swinging leaves of which are connected together for simultaneous movement in opposite directions so that when one pneumatic is expanded the other will be collapsed. These two pneumatics are connected to the pipes 63 and 64 respectively. The swinging leaves 75 of the pneumatics 93 and 94 carry a pointer 95 which is extended over the face of the music sheet 16 so that, if the music sheet be provided with a tempo line, such as is commonly found in music prepared for use in 80 players equipped with a metro style, the operator, by causing the end of the pointer 95 to substantially track with the tempo line on the music sheet, by manipulation of the plunger 82, will also cause a corresponding manipulation of valve 86 in such manner as to vary the speed of movement of the music sheet, in a manner to be described.

Arranged in the tubes 11 and 12 are throttle valves 101 and 102. These valves 101 and 102 may be duplicates and they are only shown diagrammatically in Fig. 1. A convenient form for this valve, as well as a pneumatic actuator therefor, is shown in Fig. 3 where the valve 101 is shown as a 95 swinging balanced plate conveniently elliptical in form so that it may either lie axially within its tube 11 so as to practically leave an undisturbed passage therethrough, or, by a swing of less than 90°, accurately close the 100 tube. By providing a pivot shaft 103 for this valve diametrically of the tube 11 the valve is substantially balanced in all of its positions irrespective of the force of any air traveling through the tube and consequently 105 may be swung to and held in any desired position by the exertion of a very small force. Each shaft 102 is shifted by a suitable pneumatic 111 and in the form shown in Fig. 3 is provided with a crank arm 104, 110 the pin 105 of which is engaged by one end of a link 106 the other end of said link being pivoted upon a pin 107 projected laterally from a guide rod 108 which is secured by a head 109 to one of the outer rings of a 115 multi-pouch pneumatic 111' which may be conveniently formed by connecting a plurality of rings of very light rubber sheet, in the manner illustrated in Fig. 5, the other outer ring of said pneumatic 111' being connected by a nipple 112 with a support 113 which may be readily attached to the tube 11, (or any other tube). The support 113 also carries a finger 114 to serve as a guide for the rod 108 which, within the pouch 120 111', is conveniently provided with a needle-like extension 115. In Fig. 1 I have not attempted to indicate any of the details of construction of the apparatus shown in Fig. 3 because the scale is entirely too small. 130

The pneumatic 111 or 111', is connected to pipe 68 and, with pipe 46 and ball 42', there is produced a closed pneumatic train which, when assembled with the ball 42' distended, 5 has the pneumatic 111 collapsed so that, by exerting pressure upon ball 42' so as to collapse it, the pneumatic will be expanded and valve 101 thus swung toward closed position. Similarly, the valve 102 may be 10 manipulated by means of a pneumatic 117 which is in all respects like the pneumatic 111' and is connected to its valve 102 by mechanism like that shown in Fig. 3. In the general view of the drawings, because of 15 the smallness of the scale, the parts 111 and 117 are conventionalized for convenience in illustration and also to indicate that, while the specific construction shown in Fig. 5 is desirable, other forms of pneumatic may be 20 used if desired.

As is well known, power pneumatics like the pneumatics 23 and 29 which are used for automatically operating the sustaining pedal rail and soft pedal rail, may be manipulated by opening and closing communication between atmosphere and the interior of a pipe which leads to the "secondary" of the power pneumatic. In order therefore to control the power pneumatic 23 from the 25 hand piece 41 I provide an apparatus like that shown in Fig. 4, said figure being about full size. This apparatus consists of a base plate 121 to which is secured a T tube 122 the head of the T being insertible into any 30 pipe line, as for instance, into the end of pipe 25 or into an intermediate point of its length in case the piano mechanism is of that type which is provided with an ordinary means controlled from the tracker 35 board for manipulating these power pneumatics 23 and 29. The shank of the T tube 122 is closed by a puppet valve 123 which is controlled by a swinging arm 124 pivoted at 40 125 to plate 121, the valve 123 being normally held in closed position by a spring 126 acting on arm 124. Between plate 121 and arm 124 is a pouch pneumatic 127 provided with a nipple 128 to which a tube, as for instance, tube 67, may be connected. For the 45 sake of brevity the entire valve mechanism shown in Fig. 4 may be conveniently designated by a letter V. Similarly pipe 32 is provided with a valve mechanism V the pouch of which is connected with the 50 tube 61.

In the rewinding of a music sheet, it is common experience to have the motor continue its rewinding operation for a number of turns after the music sheet has been 55 completely rewound, resulting in a noisy flapping of the initial end of the music sheet. If desired, this noise may be prevented by providing a throttle valve 131 in pipe 19 and providing an ordinary power pneumatic 132 for operating the same, said power pneu-

matic having its secondary connected to a pipe 133, the initial end of which is brought into or adjacent the tracker board 17 so as to be normally closed by the music sheet. By this arrangement, whenever the initial 70 end of pipe 133 is uncovered, the throttle valve 131 will be closed if there is any vacuum in chamber 10.

When the instrument is being controlled, through the medium of my improved hand 75 piece, from a point distant from the instrument, the vacuum within chamber 10 cannot be produced by the same operator and as the force of actuation of the string-striking pneumatics (the pneumatic action 80 15) is dependent not only upon the positions of valves 101 and 102, but also upon the amount of vacuum in chamber 10, it is desirable that some automatic means be provided by which valves 101 and 102 cannot 85 be closed so far (by manipulation of the hand piece) as to prevent actuation of the pneumatic action 15. For that reason, the stem of valve 101 is provided with an arm 161 which travels, during the closing movement of the valve 101, in the path of movement of the movable member of a pneumatic 162 which is connected by a pipe 163 with chamber 10, the said movable member of pneumatic 162 being drawn in one direction 90 by a spring 164. When there is no vacuum in chamber 10, the movable member of pneumatic 162 will lie against arm 161 so as to prevent any closing movement of valve 101 by pneumatic 111. As the vacuum in 100 chamber 10 is increased, the movable member of pneumatic 162 will be drawn farther and farther away from arm 161 so as to increase the possible range of movement of valve 101 in direct proportion to the vacuum 105 in chamber 10. Similarly the range of movement of valve 102 is automatically determined by a pneumatic 162' connected by a pipe 163' with chamber 10.

It is desirable to control the motor of the 110 music sheet, not only as to its normal speed for the production of music at any desired tempo, but also to be able to temporarily increase or diminish the speed relative to the adjusted normal. For that purpose I have 115 devised the arrangement shown in Fig. 10. In this figure 860 indicates the throttle valve of the motor (corresponding exactly with valve 86 in Fig. 1) and this valve may be shifted by crank 870 and a pneumatic 120 500 which is connected by tube 50 with a pneumatic 502 mounted on a movable carrier 503. The movable leaf of pneumatic 502 is connected by a link 504 with one arm of an operating lever 505 held yieldingly in an 125 intermediate position by a spring 506, the arrangement being such that the capacity of the pneumatic 502 may be varied by swinging lever 505 and also such that the capacity of the pneumatic 502, relative to 130

the normal position of lever 505 may also be varied by shifting the pneumatic, with its carrier 503 bodily toward or from the normal position of the operating lever.

5 The shifting of the carrier 503 may be accomplished by any desired means, as by the eccentric 507 and strap 508 carried by the eccentric and connected to the carrier. To indicate the position of the carrier, eccentric 507 may carry an indicator finger 509 arranged to traverse a tempo scale 510. In operation finger 509 is shifted to indicate the desired tempo and this movement, through eccentric 507, link 508, and carrier

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580

It is thought that the operation of my device is readily apparent from the preceding description. The several portions of my improved hand piece and their connections operate independently each unit comprising a closed pneumatic train, the final pneumatic of which is controlled in its operation and position by a manipulation of the initial pneumatic. By "pneumatic" as used in the preceding sentence and in most instances in the preceding description, I mean an element containing a fluid and capable of collapse and expansion either by means of an externally applied force or by reason of a transfer of fluid internally relative to such element.

40 The controlling valve structure, like that shown in Fig. 3, is most conveniently so formed that its tube 11 will be a short nipple readily insertible in the air line of an existing player mechanism, so that my device may thus be readily placed in commercial player pianos.

In the form shown in Fig. 9, the elements are substantially the same except that instead of providing a hand piece 41 which 50 may be carried to and operated from a distant point from the piano, the operating balls 42', 43', 44' and 45' and the pneumatics 71, 72, 73, and 74 together with the associated parts are arranged substantially 55 as permanent fixtures in the key board of the piano immediately adjacent the free ends of the keys.

In Fig. 11, I have indicated diagrammatically string-striking mechanism S designed to operate against the string s, the operation being accomplished by pneumatic action P, the drawing being intended merely to indicate in the most general way any desired or desirable form of string-striking mechanism.

I claim as my invention:

1. In a piano player, the combination of a plurality of controlling valves for independently controlling various elements of the player mechanism, a plurality of expansive and collapsible fluid tight members arranged each adjacent one of said controlling valves and connected thereto, a hand piece comprising a main body which may be grasped in the hand of an operator and also comprising a multiplicity of expansive and collapsible members arranged for manipulation by the fingers of the grasping hand of an operator, and fluid tight connections between the several expansive and collapsible members of the hand piece and the corresponding expansive and collapsible members adjacent the controlling valves. 70 75 80

2. In a piano player, a wind trunk, means for establishing an air current through said trunk, a controlling valve arranged in said trunk, means for shifting said valve to various positions between its limits, a stop for variably limiting the valve in one direction, and a pneumatic controlling said stop, said pneumatic having a connection with the means for establishing an air current through the wind trunk. 85 90

3. In a piano player, the combination with means for actuating the sound producing members of the piano, a controller for determining the force of such actuation, and means by which said controller may be variably positioned within its limit of movement, a stop for determining the limit of movement of said controller in one direction, and means for shifting said stop to various limiting positions, said means being connected with and operated by a portion of the means for actuating the sound producing members. 105

ing members.

4. In a player piano, the combination with sound producing mechanism, a wind chest forming part of said sound producing mechanism, and means for producing a differential air pressure in said wind chest, of a controlling valve arranged between said wind chest and the sound producing mechanism, means for variably positioning said valve within the limits of its movement, a stop for variably limiting said valve in one direction, a pneumatic controlling the position of said stop, and a connection between said pneumatic and the wind chest.

5. A controlling hand piece for piano 120
players comprising a main body which may
be substantially inclosed within the confines
of the fingers of one hand of an operator, a
plurality of expansible and contractible air
chambers carried by said main body, and 125
individual conduits leading from said
chambers.

chambers. 6. The combination, of a piano, mechanical means for automatically sounding the same comprising individual string-vibrat- 130

ing members and individual motors therefor controlled by a music-sheet, and also comprising a music-sheet motor, a main controller by which the force of operation of 5 a group of string-sounding motors may be controlled, a controller by which the speed of the music-sheet motor may be controlled, and a controlling hand-piece which may be arranged at a distance from the piano, and of such size and form as to be substantially inclosed within the confines of the fingers of one hand of an operator, said hand-pieces comprising a movable member connected to and controlling the said main 10 controller, said hand-piece also comprising a movable member connected to and controlling the music-sheet-motor-controller.

7. The combination, of a piano, mechanical means for automatically sounding the 20 same comprising individual string-vibrating members and individual motors therefor, a main controller by which the force of operation of a group of string-sounding motors may be controlled, and a controlling hand-25 piece which may be arranged at a distance from the piano and of such size and form as to be substantially inclosed within the confines of the fingers of one hand of an operator, said hand piece comprising a movable 30 member connected to and controlling the said main controller.

8. The combination with a mechanical musical instrument comprising individual sound producing members, means for individually operating said members, a music 35 sheet for controlling the movement of said sound producing devices, a motor for driving said music sheet, means for controlling the speed of said sheet motor, and means for 40 controlling the force applied for the individual operation of the sound producing devices, of a hand piece of such size and form as to be substantially inclosed in the confines of the fingers of one hand of an operator 45 and flexibly and distantly connected with said instrument, said hand piece comprising a movable member connected with and controlling the position of the means for controlling the speed of the sheet motor 50 and also comprising a movable member connected with and controlling the means for

controlling the force applied to the sound producing mechanism.

9. The combination, with a piano and pneumatic playing apparatus therefor comprising individually operable sound producing members, pneumatic motor members connected with said sound producing devices, a valve for controlling the force of said pneumatic motors, a valve motor associated with said valve for moving the same, a music sheet for controlling the operation of said pneumatic motors, a wind motor for driving said music sheet, a valve for controlling the speed of said wind motor, and 60 a second motor for moving said wind motor valve, of a hand implement flexibly and distantly connected with said pneumatic playing apparatus, said hand implement being of such size and form as to be substantially 65 inclosed within the confines of the fingers of one hand of an operator and comprising a movable member connected with and controlling the operation of the first mentioned valve motor, and also comprising a second 70 movable member connected with and controlling the last mentioned valve motor.

10. The combination with a musical instrument having a plurality of sound producing elements, means by which said sound 80 producing elements may be automatically manipulated, and a controller for said automatic mechanism said controller being in the form of a hand-piece which may be substantially inclosed within the confines of 85 the fingers of one hand of an operator and comprising a multiplicity of movable members individually operable by the fingers of the operator, and means controlled by the several individually operable members of 90 the hand-piece for independently controlling the action of portions of the automatic mechanism.

In witness whereof, I have hereunto set my hand and seal at Indianapolis, Indiana, 95 this 12th day of December, A. D. one thousand nine hundred and twelve.

ALEXANDER JAMESON. [L. S.]
